United States Patent Office.

CHENEY KILBURN, OF PHILADELPHIA, PENNSYLVANIA, ASSIGNOR TO
KILBURN & GATES, OF SAME PLACE.

Design No. 4,316, dated August 30, 1870.

DESIGN FOR BOXES FOR THE TOPS OF BUREAUS.

The Schedule referred to in these Letters Patent and making part of the same.

I, CHENEY KILBURN, of Philadelphia, county of Philadelphia, State of Pennsylvania, have invented or produced a Design for Boxes for the Tops of Bureaus, of which the following is a specification.

Figure 1 is a perspective view illustrating my design for a box for the tops of bureaus;

Figure 2, a plan view of the same, in outline; and Figures 3 and 4 views of modifications.

My design relates to boxes placed on bureaus, and forming bases for looking-glass stands, and consists of the peculiar shape and configuration of such boxes, as explained hereafter.

The design consists in forming the fronts of such boxes with a number of angular faces, *a b c d, &c.*, instead of making them flat or rounded, as usual.

The front of the box represented in figs. 1 and 2, for instance, is a section of a polygonal figure of

twelve sides, the box represented in fig. 3, the section of an octagon, and the box shown in fig. 4 a section of a fourteen-sided figure.

It should be understood that I do not confine myself to any specific number of faces or angles, or to any specific moldings for ornamenting the same; but

I claim—

The design for boxes for the tops of bureaus, substantially as described, and as represented in and by the accompanying drawing.

In testimony whereof I have signed my name to this specification in the presence of two subscribing witnesses.

CHENEY KILBURN.
